UNITED STATES PATENT OFFICE.

LINCOLN A. MERRIAM, OF NEW YORK, N. Y.

AMALGAMATOR.

SPECIFICATION forming part of Letters Patent No. 252,051, dated January 10, 1882.

Application filed October 8, 1881. (No model.)

To all whom it may concern:

Be it known that I, LINCOLN A. MERRIAM, a citizen of the United States, residing in the city, county, and State of New York, have invented new and useful Improvements in Apparatus for Extracting the Precious Metals by the Quicksilver Process, of which the following is a specification.

The invention relates to amalgamators for mixing quicksilver with ores for the purpose of extracting from them the precious metals. The processes heretofore resorted to have been operated upon the theory that in the agitation of the ore over the quicksilver the metals would settle upon and be taken up by it. To an extent this is true; but it is found that a considerable per cent. still passes off with the ore, to the great loss of the operator. Efforts have also been made to mix the ores and quicksilver; but on account of the great specific gravity of the quicksilver and its mobility the result has been thus far unsatisfactory.

The object of my invention is an apparatus by which the ore is inducted into the amalgamator with precision and certainty and retained and thoroughly mixed with the quicksilver in its passage upward through it.

Figure 1 of the drawings shows, in vertical section, the amalgamator. Fig. 2 is a cross-section.

B is an induction-pipe, having the piston-valves e e' , the discharge-pipe b , the rotating mixer C, the gear c , and the overflow a .

r is the connecting reciprocating rod working the piston-valve e' and moving in the hollow shaft of the mixer C.

To prevent packing, the ore in B may be agitated, as in A, by a modification of C, or other suitable device.

x is one or more perforated flanges projecting internally in A, and A is separable at the joint i .

The amalgamator A is charged with quicksilver, and has an inverted siphon-pipe, B, opening through its bottom for the passage of the ore. On entering A the ore is struck and scattered by C, and the flange or flanges x hold it in contact with the quicksilver until it gradually passes upward through the openings and passes off at a . C is rotated rapidly by means of the gear c or other suitable device.

A sluice may be placed under a to arrest pyrites, or a screen may be used for that purpose, or at the induction end of the pipe B. The enlargement of B from the level of the quicksilver tends to prevent packing, and also gives room for working the valve e , when needed, as auxiliary to gravity-pressure of the pulp or ore descending through the induction pipe in effecting the passage of the ore. These pump-valves may be constructed in any of the known ways.

To draw off the amalgam for separating the metals, open the valve b , which may be constructed in any of the known ways.

The suction-piston containing the valve e' is intended to operate as auxiliary to the gravity-pressure of the ore in the receiving end of the pipe B, and, by drawing it toward the amalgamator at the point where an obstruction might be forming, prevent a clogging that no mode or increase of pressure from above would remove; and the check-valve e is to prevent the movement of any substance in the amalgamator A upward through the pipe B. The amalgamator A may be open at the top and charged with quicksilver by pouring it in.

What I claim is—

1. In apparatus for extracting the precious metals from their ores, the amalgamator A, having the cross-plates x , the expanding induction-pipe B, the check-valve e , and the mixer C, constructed, arranged, and operating in the manner and for the uses specified and shown.

2. In apparatus for extracting the precious metals from their ores, the amalgamator A, having the perforated plates x , the induction-pipe B, the mixer C, rotating on a hollow shaft, the piston-valve e' , and the connecting reciprocating rod r , constructed and operating in the manner and for the purposes shown and described.

3. In apparatus for extracting gold and silver from their ores, the amalgamator A, having the induction-pipe B, the check-valve e , the piston-valve e' , the connecting reciprocating rod r , and mixer C, rotating on a hollow shaft, arranged and operating in the manner and for the uses specified and described.

4. In apparatus for amalgamating the precious metals, the amalgamator A, separable at

i, and having the perforated plates or flanges *x*, the mixer *C*, rotating on a hollow shaft, the expanding induction-pipe *B*, with the check-valve *e*, and the piston-valve *e'*, constructed and operating in the manner set forth and shown.

5. In apparatus for amalgamating the precious metals from their ores, the amalgamator *A*, separable at *i*, having the perforated plates *x*, the induction-pipe *B*, the check-valve *e*, the

mixer *C*, rotating on a hollow shaft, the piston-valve *e'*, the connecting reciprocating rod *r*, the overflow *a*, and pipe *b*, constructed and operating in the manner and for the uses substantially as set forth, specified, and shown.

LINCOLN A. MERRIAM.
